United States Patent Office

Des. 234,241

Patented Feb. 4, 1975

234,241

CHAIR

Kunio Onoguchi, Tokyo, Japan, assignor to France
Bed Co., Ltd., Tokyo, Japan

Filed Feb. 28, 1973, Ser. No. 336,439

Term of patent 7 years

Int. Cl. D6—01

U.S. Cl. D6—76

FIG. 1 is a top plan view of a chair showing my design;
FIG. 2 is a front elevational view thereof;
FIG. 3 is a bottom plan view thereof;
FIG. 4 is a right side elevational view thereof;
FIG. 5 is a rear elevational view thereof; and
FIG. 6 is a perspective view thereof.

The left side elevational view is a mirror image of FIG. 4 and is omitted.

I claim:

The ornamental design for a chair, as shown and described.
